UNITED STATES PATENT OFFICE.

JOHN STADTHERR AND ALBERT BENGTSON, OF GIBBON, MINNESOTA.

GRAIN-SEPARATOR.

1,241,045.

Specification of Letters Patent. Patented Sept. 25, 1917.

Application filed April 16, 1917. Serial No. 162,517.

To all whom it may concern:

Be it known that we, JOHN STADTHERR and ALBERT BENGTSON, citizens of the United States, residing at Gibbon, in the county of Sibley and State of Minnesota, have invented certain new and useful Improvements in Grain-Separators, of which the following is a specification, reference being had to the accompanying drawings.

10 This invention relates to certain improvements in grain separators and has relation more particularly to a device of this general character of a gravity type; and it is an object of the invention to provide a separator of this general character having novel and improved means whereby wild peas or other substantially spherical foul matter is readily separated from the grain.

It is also an object of the invention to provide a novel and improved device of this general character wherein the matter to be separated is caused to travel down an incline and wherein the lower or discharge end of the incline is provided with means for imparting an upward movement or jump to the matter and which results in the wild peas or other substantially spherical foul matter being thrown a greater distance than the grain so that the requisite separation is effected.

The invention also has for an object to provide a device of this general character having novel and improved means whereby the matter to be separated is subjected to a plurality of separating actions together with means whereby the separated grain and foul matter are independently collected.

The invention consists in the details of construction and in the combination and arrangement of the several parts of our improved separator whereby certain important advantages are attained and the device is rendered simpler, less expensive and otherwise more convenient and advantageous for use, all as will be hereinafter more fully set forth.

The novel features of the invention will hereinafter be definitely claimed.

In order that our invention may be the better understood, we will now proceed to describe the same with reference to the accompanying drawings, wherein—

Figure 1 is a vertical sectional view of somewhat a diagrammatic character taken 55 through a separator constructed in accord-

ance with another embodiment of our invention;

Fig. 2 is an enlarged fragmentary view partly in elevation and partly in section illustrating certain details of construction as 60 relates to an endless carrier as concluded in this form of our invention;

Fig. 3 is a fragmentary view partly in section and partly in top plan of the structure disclosed in Fig. 2;

Fig. 4 is a sectional view taken substantially on the line 10—10 of Fig. 3; and

Fig. 5 is a fragmentary view partly in section and partly in elevation illustrating a tensioning member adapted to be employed 70 in connection with each of the endless carriers as embodied in the latter form of our invention.

As disclosed in the accompanying drawings, C¹ denotes a casing provided in its top with 75 the hopper H² which discharges upon the top pan or member 4^d. The members 4^d at their lower ends and at a predetermined point intermediate their lengths are provided with the upwardly directed portions 80 or flanges 23. The upper flange or portion 23 of each of the pans or members 4^d serves to throw the grain upon the supplemental pan or member 24 positioned above the pan or member 4^d and positioned substantially 85 between the portions or flanges 23. The lower or discharge end of the supplemental pan or member 24 is also provided with the upturned portion or flange 25.

The grain as discharged to each of the 90 pans 4^d and the coacting supplemental pan 24 is thrown upon the endless carrier 26 disposed on a predetermined incline and having its upper stretch traveling in a direction toward the pan or member 4^d. The 95 grain received upon the upper stretch of the carrier 26 is discharged by said carrier upon the apron 27 inclined toward and discharging upon a second pan or member 4^d and it is to be observed that the lower or discharge 100 end of the apron 27 is provided with an upwardly directed portion or flange 28 whereby a further separation of the grain is effected. The portion or flange 28 serves to throw the foul matter against the shield or 105 apron 29 depending from the upper end portion of the pan or member 4^d immediately above the apron 27. The aprons or shields 29 serve to deflect the foul matter within the collecting chamber B'.

The carriers 26 are adapted to be driven in any desired manner and are preferably formed of cloth with the longitudinal marginal portions of each of said carriers provided with the reinforcing strips 30 of leather or other suitable material secured to the outer face of the cloth and which strips coact with the guides 31 in such a manner as to cause the carrier 26 to properly engage the rollers 32 around which the same is disposed. The guides 31 also serve to prevent the grain and foul matter from getting between the edges of the carriers 26 and the adjacent side of the casing C¹ and thereby preventing waste and obstruction to the travel of the carriers.

We also find it of advantage to have coacting with the lower stretch of each of the carriers 26 a tightener 33 which may be of any ordinary or preferred construction. As illustrated in Fig. 1 the tightener 33 comprises a roller 34 suitably supported by the casing C¹ and which is constantly urged toward the upper face of the lower stretch of the carrier 26 by the expansible member 35 herein disclosed as a conventional coil spring.

From the foregoing description, it is thought to be obvious that a separator constructed in accordance with our invention is of an extremely simple and comparatively inexpensive nature and is particularly well adapted for use by reason of the convenience and facility with which it may be assembled, and it will also be obvious that our invention is susceptible of some change and modification without material departure from the principles and spirit thereof and for this reason we do not wish to be understood as limiting ourselves to the precise arrangement and formation of the several parts herein

shown in carrying out our invention in practice, except as hereinafter claimed.

We claim:

1. A device of the character described comprising a plurality of inclined members discharging one upon the other, aprons depending from the upper end portions of certain of said members and endless carriers having their upper stretches traveling toward the members, each of said endless carriers receiving from an upper inclined member and delivering to an inclined member immediately therebelow. 45

2. A device of the character described comprising a plurality of inclined members discharging one upon the other, the lower ends of each of said members being disposed upwardly, aprons depending from the upper end portions of certain of said members and endless carriers having their upper stretches traveling toward the members, each of said endless carriers receiving from an upper inclined member and delivering to an inclined member immediately therebelow. 60

3. A device of the character described comprising a plurality of inclined members discharging one upon the other, and endless carriers having their upper stretches traveling toward the members, each of said endless carriers receiving from an upper inclined member and delivering to an inclined member immediately therebelow. 65

In testimony whereof we hereunto affix our signatures in the presence of two witnesses. 70

JOHN STADTHERR.
ALBERT BENGTSON.
